JAMES BOWERS, OF NEW YORK, N. Y.

Letters Patent No. 63,005, dated March 19, 1867.

IMPROVEMENT IN CORSET FASTENINGS.

The Schedule referred to in these Letters Patent and making part of the same:

TO ALL WHOM IT MAY CONCERN:

Be it known that I, JAMES BOWERS, of the city, county, and State of New York, have invented a new and improved Fastening for Corsets; and I do hereby declare that the following is a full, clear, and exact description thereof, which will enable others skilled in the art to make and use the same, reference being had to the accompanying drawings, forming part of this specification.

This invention relates to a new and improved fastening for that kind of stays or corsets which are composed of two parts, connected by a lacing at the rear part and by a fastening at the front, which will admit of the front ends of the two parts being readily connected and disconnected. The object of the invention is to obtain a fastening for the purpose specified, which will admit of the front ends of the two parts of the corsets being connected and disconnected with the greatest facility, and which will be perfectly independent of the springs, so that the latter can at any time when required be drawn from the corsets to admit of the latter being washed, repaired, etc., it being essential that the springs be withdrawn when the corsets are to be washed, otherwise the springs would rust and soil the fabric. In the accompanying sheet of drawings—

Figure 1 is a front view of my invention applied to stays or corsets.

Figure 2, a horizontal section of the same taken in the line x - x , fig. 1.

Similar letters of reference indicate like parts.

A A' represent the two parts of a pair of stays or corsets, and b b the hems, which contain the springs B. In one part, A, of the corsets, at the inner side of its hem, b, there are inserted eyelets, C, and to the front edge of the other part A' there are attached by loops, e, metal plates, d, having each two hooks, e, at their outer ends. These plates d are perfectly flat, or are planes, and of sufficient length to reach or extend over the hem and spring of the opposite part, so that the hooks e may catch into the eyelets C, the plates d being quite close to the corsets so as not to project out therefrom. The plates d, with their hooks e, do not at all interfere with the spring B of the part to which they are attached. The spring of either part may be readily withdrawn from its hem and the springs inserted in the hems without any difficulty whatever. The eyelets C of course must be inserted in the part A at points to correspond with the position of the hooks e, which are to fit into them. Two or more of these fastenings may be applied to the corsets; in general three will probably be used.

I claim as new, and desire to secure by Letters Patent—

A fastening for stays or corsets, composed of eyelets *C*, inserted in one of the parts *A* just behind its hem *b*, and plates *d*, formed or provided with hooks *e*, and attached by loops *c* to the front edge of the other part *A*, substantially as herein shown and described.

The above specification of my invention signed by me this 13th day of February, 1867.

JAS. BOWERS.
